(57) **CLAIM**

The ornamental design for beverageware handle, as shown and described.

DESCRIPTION

FIG. 1 is a perspective view of a beverageware handle showing our new design;

FIG. 2 is a right-hand side elevational view thereof, the left-hand side elevational view being a mirror image;

FIG. 3 is a front elevational view thereof;

FIG. 4 is a rear elevational view thereof;

FIG. 5 is a top plan view thereof; and,

FIG. 6 is a bottom plan view thereof.

The broken lines in FIG. 1 are for illustrative purposes only and form no part of the claimed design.
